(54) **CIDER MILL**

(76) Inventor: **Charles Rice**

*Charles Rice of Barre, Worcester Co. Massachusetts
Linen Merchant.*

*The following is to be on these Letters Patent and making part of the same
containing a description in the words of the said Charles Rice himself, of
his improvement in Cider Mills.*

*Be it known that I Charles Rice of Barre in the County of Worcester &
State of Massachusetts have made an improvement in Cider Mills
which is described as follows. This Cider Mill consists of the following
principal parts. No. 1. The carriage with the wheels. 2. The rack to receive
the punice. 3. The cylinder and hopper. 4. The Pump and screw. 5. The
bearing - i. The Carriage with the wheels. The carriage is about 10
feet long. 5 1/2 feet wide and about 4 feet high framed together and fast-
ened by screws. There are four wheels, the two forward about 3 feet, &
the two hinder about 3 1/2 feet diameter, on which the carriage rests
and by means of which it is removed from place to place.*

*2. The Rack to receive the punice. is made of staves or steds about
4 feet long and about 1 1/8 inch square and the rack may be either cir-
cular or rectangular, placed prospectively. If circular the lower ends
of the staves or steds are cut into an opening on the floor of the carriage -
with a hoop and rivets to bind them together at that place. If rectangular
then the staves or steds may be fastened into the upper and lower part of
the carriage. 3. The cylinder and Hopper. The cylinder is about 11 inches
long and 8 inches diameter turning on guides, resting on two beams and directly
over the Pump to be hereafter described. On this cylinder are 8 or 10 rows of points
placed in a spiral direction and covering the cylinder from side to side. In the hop-
per placed over the cylinder is an iron bar spikes which comes nearly but not quite
in contact with the points of the cylinder. 4. The Pump and screw. The Pump is
formed by 4 beams about 6 feet long and 1 3/4-inch diameter, with a following
beam fastened to the lower ends. This follower is made of two beams with screws passing
diagonally through them. The floor of the follower consists of three pieces, which can
be taken out at pleasure to remove the punice. On the top of the rack are placed
strong iron blocks turned the fore and aft to the punice. On the top of each come*

is a not working against another rolling on the base of the carriage, and sliding board is placed at the bottom of the carriage where the juice falls and is collected.

3. The Beating is done by a roller in common use and is adapted to the purpose of the mill. This Cider mill may be worked by animal, water, and steam power.

Operation. The apples are put into the hopper. The mill is set in motion the apples are ground by the cylinder, the juice descends into the press, upon the bars of the follower. The Planks being placed down the top of the sack, the stones are turned by a wheel which bring up the follower with the planks against them, and thus the juice of the apples is pressed out. The juice falls down and is collected on the sliding board from whence it runs into a trough or tile, the juice is taken out by removing the bars of the follower.

The Inventors here claim, and for which Letters Patent are desired in the U.S. the Back, and the arrangement of the different parts of the mill as above described. I wish to illustrate my invention. I refer the model and drawing of the same deposited in the Patent Office. I testimony that the foregoing is a true description of my invention. I have signed my name before two witnesses and made oath to the same at the City of Washington this 25th day of November 1830.
